FIG. 1 is a perspective view of an internally lighted crystal prism mirror light for vehicle showing my new design;
FIG. 2 is a front elevational view thereof; with the exception
of a suspension base thereof, the rear elevational view
thereof is identical thereto;
FIG. 3 is a right side elevational view thereof; with the
exception of the suspension base thereof, the elevation view
of the other sides are substantially identical thereto;
FIG. 4 is a top plan view thereof;
FIG. 5 is a bottom plan view thereof; and,
FIG. 6 is a perspective view showing the internally lighted
crystal prism mirror light for vehicle in use; the broken lines
depict environmental structure for illustrative purposes only
and form no part of the claimed design.
